URETER BLOCK FOR USE IN PYELOGRAMS

David R. Stanford, Renton, Wash.

Application October 2, 1950, Serial No. 187,956

3 Claims. (Cl. 128—1)

1

My invention concerns compression means for blocking the ureters during the taking of pyelograms; and, more particularly concerns the use of a block of radiolucent material, such as balsa wood, adapted to compress the ureters in the sacroiliac region to dam X-ray opaque materials in the urinary system.

Examination of the ureters is now frequently and successfully accomplished by intravenous pyelography, thus producing a satisfactory study without subjecting the patient to the discomfort of a retrograde examination. In this method, X-ray opaque material is intravenously injected while the patient reclines on a table below the X-ray machine. The opaque material tends to move too rapidly through the urinary system to sufficiently delimit the ureters unless some means is used to impede the flow. A common method of blocking the ureters to retain the opaque material is to depress an air-inflated rubber ball, such as a football bladder, into the patient's body, to compress the ureters in the sacroiliac region. Such ball or bladder, however, is an unsatisfactory member to use for such blocking action. One fault is that the bladder is made of rubber which is partially X-ray opaque and the skiagram is obscured in the area of the blocking member. Another fault is that the bladder is not designed for such use and when it accomplishes the function of blocking the ureters it does so in spite of its shape. The bladder compresses a wide area instead of just the points where the ureters pass the sacroiliac region, and the patient suffers additional unnecessary discomfort and the ureters may not be sufficiently blocked. The upper portion of the rubber ball or bladder is not adapted for applying the compressing force, as by use of a band secured at one end to a side of the table and having tightening means at the other end secured to the other side of the table.

The objects of my invention, therefore, include: to provide compression means for blocking the ureters during the taking of pyelograms; to form said compression means of substantially radiolucent materials so the skiagram is not obscured in the area of the compression means; to provide an improved design for the compression means to accomplish the function of blocking the ureters in the sacroiliac region; to minimize the discomfort of the patient during the taking of pyelograms and to provide more efficient means for accomplishing the examination; and to adapt the blocking means to facilitate the application of compressive force on said means.

Briefly, the foregoing objects are accomplished in my invention by the following structure: A blocking member is constructed from some substantially radiolucent material such as balsa wood. The top portion of the block is substan-

5 tially rectangular to be positioned with its longitudinal axis running crossways of the human body. The block has two depending portions, the depending portions joining at their upper portions and dividing at their lower portions. The lower portions have horizontal cross sections substantially in the form of rectangles with rounded corners. Each lower portion has convex sides and a bottom which is slightly convexly curved transversely of the human body. The bottoms of the lower portions have their centers spaced apart one from another substantially the distance that the average ureters are spaced apart in the sacroiliac region. When the depending portions are depressed, they are in position to effectively block the ureters with a minimum of disturbance of the organs. The top portion is flat and of substantial width, forming a suitable surface for the applying of pressure on the block, as by use of a band secured at one side of the table on which the patient reclines and having tightening means at the other end secured to the other side of the table.

20 My invention and the manner in which these and other objects are accomplished, will be best understood from the following detailed description of a specific embodiment of my invention, when read with reference to the accompanying drawings, in which:

25 Figure 1 is a perspective view looking upwards at the bottom portion of a specific embodiment of my ureter compressing block;

Figure 2 is a front view of the block;

Figure 3 is an end view of the same;

30 Figure 4 is a perspective view of a patient reclining on a table with said block in position to be urged downward by a compression band; and

Figure 5 is a plan view, in fragmentary form, showing the urinary system and certain bones 35 of the skeleton, with the positioning of ureter compressing block indicated in dotted lines.

40 My ureter compression block should be constructed from some substantially radiolucent material. Balsa wood has proven to be quite satisfactory for this purpose, and is shown in the drawings. Any substantially X-ray opaque material obscures the covered area of the ureters in the skiagram. Usually two X-rays are taken while the X-ray opaque material is contained in 45 the kidneys and ureters, one while the ureters are blocked and one shortly after the ureters are freed to show the lower part of the ureters while they still contain X-ray opaque material. In order to clearly show the ureters in these two X-rays, it is important to be able to show all of that 50 portion of the ureters to the point of compression in the first X-ray. If an X-ray opaque compression device is used, the portion of the ureters adjacent the point of damming is obscured. When a balsa block is used, the covered

area of the ureters appears quite satisfactorily on the skiagram.

Block 10 is composed essentially of top portion 12 and depending portions 14 and 16. Top portion 12 is substantially rectangular with rounded corners, preferably, even though other shapes could be used. Top surface 18 is flat and with this construction a good surface is provided for application of force, as by compression band 20, shown in Figure 4. Ends 21 are rounded facilitating movement of the block along band 20 for adjustment of the same. Band 20 has considerable width affording stability, and top portion 12 is of a width to accommodate band 20. Depending portions 14 and 16 do not need such width to perform their compressing function and top portion 12 overhangs them on all sides.

Depending portions 14 and 16 are joined at their upper portions, as at 22, for strength and convenience of manufacture, and separate, forming two lower portions 24 and 26. Lower portions 24 and 26 are substantially rectangular with rounded corners in horizontal cross-section and have convex sides. Depending portions 14 and 16 could be formed somewhat differently, the most important feature being the providing of two bottom surfaces 30 and 32. Having the bottom surfaces divided provides for maximum compression of the ureters and minimum disturbance of other parts of the body. Bottom surfaces 30 and 32 are of substantial size to accommodate the various positions the ureters may assume in different persons. Bottom surfaces 30 and 32 are slightly convexly curved transversely of the body but are substantially straight longitudinally of the body.

Referring to Figure 4, the patient is shown reclining on table 40. Band 20 is secured at one end and the other end is secured by adjustable means for tightening the band. The adjustable means include a shaft supported by brackets 42 and handle 44 is connected to the shaft to rotate the same. Some means for adjustably securing the shaft should be provided, as by a ratchet and pawl assembly. Normally an X-ray is taken before block 10 is positioned, for orientation. Then block 10 is positioned as shown in Figure 4 and the X-ray opaque material is usually intravenously injected before band 20 is tightened. As band 20 is tightened, depending portions 12 and 14 are depressed until bottom surfaces 30 and 32 compress the ureters. Block 10 may be shifted as band 20 is tightened, in which case it may be rocked back into position by hand. One X-ray is usually taken while the ureters are blocked and one is taken shortly after compression is relieved.

In Figure 5 the positioning of bottom surfaces 30 and 32 is indicated in dotted lines at 50. Pressure is over the sacrum 52 and the sacroiliac area 54. Occasionally part of the pressure is on the fifth lumbar vertebra 56. One way to locate bottom surfaces 30 and 32 is to position their ends toward kidneys 58 about two fingers below the crest 60 of ilium 62. Ureters 64 may vary in spacing in different patients from six to nine and one-half centimeters so the centers of bottom surfaces 30 and 32 should be spaced approximately the distance of the average spacing of ureters and they should be wide enough to apply direct pressure throughout the normal range of spacing of ureters. The first X-ray after injection of X-ray

opaque material obtains a view of kidneys 58 and upper portion 66 of ureters 64. After pressure is removed, a view of lower portion 68 of ureters 64 is obtained leading to bladder 70.

It will be apparent from the above description that I have conceived of improved radiolucent compression means for blocking the ureters during the taking of pyelograms, in which the blocking is efficiently accomplished and with a minimum of discomfort to the patient. While I have described a specific embodiment of my invention, I do not wish to be understood as limiting myself to that embodiment, but wish to claim all modifications within the fair scope of my invention.

I claim:

1. Compression means for blocking the ureters during the taking of an X-ray of the urinary system, comprising: a balsa wood block having the characteristic of being substantially radiolucent, said block to be positioned on the human body above the sacroiliac and depressed to dam the ureters in that region, said block having a top portion which is substantially rectangular and elongated and having two depending portions, said depending portions being joined at their upper portions and dividing at their lower portions, said lower portions having horizontal cross sections substantially in the form of rectangles with rounded corners throughout most of their extensions, said lower portions being spaced apart one from another in a direction which is longitudinal of said top portion, each lower portion having convex sides and a bottom which is slightly convexly curved in a direction which is longitudinal of said top portion, said bottoms of said lower portions having their centers spaced apart one from another substantially the distance that the average ureters are spaced apart in the sacroiliac region.

2. Compression means for blocking the ureters during the taking of a pyelogram, comprising: a balsa wood block having the characteristic of being substantially radiolucent; said block having a top portion and two depending portions extending downward a considerable distance; said depending portions having their lower portions slightly rounded and having the crests of said lower portions spaced apart one from another substantially the distance that the average ureters are spaced apart in the sacroiliac region.

3. Compression means for blocking the ureters during the taking of an X-ray of the urinary system, comprising: a block having the characteristic of being substantially radiolucent, said block having a top portion and two depending portions extending downward a considerable distance, said depending portions having their lower surfaces spaced apart one from another such a distance that the ureters in the sacroiliac region are compressed upon depression of said block into that region.
